GOLF CLUB HEAD

John R. Green, Jr., 4804 Starmount Drive,
Greensboro, N.C.

Filed June 16, 1960, Ser. No. 60,987

Term of patent 14 years

(Cl. D34—5)

FIG. 1

FIG. 2

FIG. 3

FIG. 1 is an elevational view from the back side of a golf club head, showing my new design, the opposite side is substantially plain;

FIG. 2 is an end elevation taken from the right or outer end of the golf club head as shown in FIG. 1; and

FIG. 3 is a top view of the golf club head of FIGS. 1 and 2.

I claim:

The ornamental design for a golf club head, as shown and described.
